LLP; D. Scott Hemingway; Elizabeth P. Hartman(57) CLAIM

The ornamental design for a fireplace surround, as shown and described.

DESCRIPTION

FIG. 1 is a front perspective view of a fireplace surround of the present application;

FIG. 2 is a front elevation view of FIG. 1;

FIG. 3 is a rear elevation view of FIG. 1;

FIG. 4 is a right side view of FIG. 1;

FIG. 5 is a left side view of FIG. 1;

FIG. 6 is a top view of FIG. 1; and,

FIG. 7 is a bottom view of FIG. 1.

The broken lines shown in the drawings set forth in FIGS. 3 and 7 are for the purpose of illustrating portions of the fireplace surround and form no part of the claimed design.
